FOLLOWER FOR CARD FILES

William M. Gerkey, Joplin, Mo.

Application September 27, 1937, Serial No. 165,957

2 Claims. (Cl. 129—30)

My invention relates to followers which are used in connection with file boxes intended to receive and hold record cards. It has for its object to provide an improved follower constructed entirely of metal parts that may be easily fabricated and which are of simple construction, and therefore may be made and supplied to the trade at small cost. The follower is constructed to be set within the box or container for the cards and to have frictional engagement directly with the walls thereof, being held in place by such engagement and without resort to any supplemental attachments secured to the container itself.

15 The invention is illustrated in the accompanying drawing, wherein—

Figure 1 is a transverse sectional view taken just to the rear of a follower made according to my invention and represented as in position holding cards which have been placed within the box or container;

Fig. 2 is a central longitudinal sectional view taken on the line 2—2 of Figure 1;

Fig. 3 is a detail face view of the follower illustrating the reversibility in use of one of its parts;

Fig. 4 is a perspective view of the retaining slide portion of the follower; and

Fig. 5 is a perspective view of one of the movable clamping members thereof.

30 Referring to the drawing, A represents a container adapted to receive record cards B. It is illustrated as being of open-top box construction commonly employed as file boxes.

The follower, constituting the subject of my invention, consists of a slide piece C adapted to be set into the box A behind the cards which are to be held in place thereby; a pair of laterally movable friction members G supported by the slide member C and adapted to have frictional engagement directly with the inner surfaces of the side walls of the box; and a spring F located between the two friction members for forcing them into engagement with the wall of the box.

The slide C and the friction members G are formed of sheet metal. Along the upper and lower edges, respectively, of the retaining slide C are formed guides or slideways c, c, by turning over such edges, as clearly represented in Fig. 4. Each slideway is divided, the upper one by a cut-out portion of the slide, as represented at c', forming a finger space giving access to the cards; and the lower one by a footing piece D, integral with the slide piece and serving to support the slide in proper position to engage with the cards, when the slide is in use. The two sets of slide-

ways thus formed, one at either end of the follower, serve to support the two friction members G, the top and bottom edges of which latter are adapted to move in the runways formed by the overturned edges c of the follower. The length of each friction piece is less than half the length of the main slide C of the follower so that there may be located between them the spring F that operates to force them apart and into lateral engagement directly with the inner walls of the 10 sides of the box. While the spring F may be of any suitable construction, I prefer that it should be formed of spring metal and that it should be held at its center by an integral part of the metal constituting the slide piece C. This may 15 well be provided by stamping out a portion of the metal and folding it over, as represented at E in Figures 2 and 4.

In order that the spring F may have engagement with the friction pieces G, and that the latter may be engaged by the user of the device to release the follower from frictional engagement with the walls of the box, the inner edges of the parts G are bent or turned at right angles to the main body portion thereof forming flanges H. These flanges are of a length less than the height of the clamping pieces G so as not to interfere with the clamp parts freely running in the slideways c.

At their outer edges the clamping pieces are 30 preferably formed with flanges located at right angles to the main body portions of the pieces G, so as to lie substantially parallel to the inner walls of the box when the follower is applied for use to retain the cards, as clearly indicated in 35 Figures 1 and 3.

I prefer that the end flanges I of the movable clamping parts, which have direct engagement with the inner walls of the box sides, should be, in part at least, resilient. To that end each flange I is cut away along the line of its connection with the end body portion of the clamp piece, as represented at i, Figure 5, and the free end J thus formed is shaped to have good frictional engagement with the wall of the box, the engaging surface being rounded and smooth.

If it be found that the friction of the elastic end portion of the metallic flange with the wall of the box is not sufficient for desired holding effects, a rubber friction pad in the form of a 40 band K may be used, as indicated in Figure 5.

The transversely movable friction members G of the follower are reversible, as will be apparent by a comparison of Figures 1 and 3. I prefer 45 that the elastic ends of the end flanges of the 50

clamping pieces should extend upwardly, thus engaging with the side walls of the box near its upper open end, as represented in Fig. 1. However, where the box such as A' is formed of thin and comparatively weak material, perhaps paper board, it is found that the pressure of the clamping pieces, engaging with the walls of the box near its upper open end, tends to cause a bulging of the sides, thus weakening the grip of the follower upon the box and lessening its efficiency. In such a case the friction slide pieces G are reversed, as indicated in Fig. 3, so that the elastic ends J of the clamping flanges engage with the sides of the box near their lower edges, where they join the bottom of the box, the box being therefore of sufficient rigidity to stand the pressure of the clamping parts of the follower without materially yielding.

It will be understood that when the clamp is to be applied or is to be moved after application, the user will move the two clamping members G toward each other, compressing the spring F, by engaging with the fingers the inner flanges H. Upon releasing the clamping members the spring immediately forces them apart and into a holding engagement with the side walls of the box.

While the form of invention which I have described and illustrated, comprising a pair of frictional transversely movable clamping plates, is that which I prefer and which I deem to be of the greatest advantage, it is evident that the invention is not limited to the specific disclosure herein made. For instance, many of the advantages of my invention could be attained in a construction wherein but a single transversely movable slide plate for frictional engagement directly with the wall of the box was employed. The main supporting transverse plate would in that case be constructed to bear against the opposite wall of the box to that engaged by the sliding friction plate.

What I claim is:

1. A follower for a card file box comprising a rectangular sheet metal plate, the upper and lower edges of which are reversely bent to provide parallel guideways, said lower edge being also provided with an integral angularly extending supporting foot, and a portion of said plate

above said foot being struck out and rolled to constitute a spring supporting member; a pair of reversible friction members slidably mounted in said guideways, one to either side of said spring supporting member, said friction members comprising sheet metal plates each having its lateral edges bent rearwardly to provide respectively a finger piece and a flange adapted to frictionally engage with a wall of the card file box; and a spring embraced and securely held by said spring supporting member with its opposite end portions engaging said finger pieces, said spring normally urging said slidable friction members in opposite outward directions to maintain their wall engaging flanges in engagement with the file box walls. 5 10 15

2. A follower for a card file box comprising a rectangular sheet metal plate, the upper and lower edges of which are reversely bent to provide parallel guideways, said lower edge being also provided with an integral angularly extending supporting foot, and a portion of said plate above said foot being struck out and rolled to constitute a spring supporting member; a pair of sheet metal plate members slidably mounted in said guideways, one to either side of said spring supporting member, said sliding plate members each having its lateral edges bent rearwardly to provide respectively a finger piece and flange adapted to engage with a wall of the card file box, an end portion of each of said flanges being severed from its plate to impart resilience thereto, said end portions of the flanges being also bulged outwardly for frictional engagement with the box walls; said slidable plate members being readily removable and transversely interchangeable and reversible in said guideways whereby the bulged portions of said flanges may be caused to engage said box walls adjacent either its top or its bottom; and a spring embraced and securely held by said spring supporting member with its opposite end portions engaging said finger pieces, said spring normally urging said slidable plate members in opposite outward directions to maintain said bulged ends of the flanges in engagement with the box walls. 20 25 30 35 40 45
